(57) **CLAIM**

We claim the ornamental design for a key operated cam lock with hook-shaped cam, as shown and described.

DESCRIPTION

FIG. 1 is a front view showing one embodiment of our new design;

FIG. 2 is a left side view thereof;

FIG. 3 is a right side view thereof;

FIG. 4 is a rear view thereof;

FIG. 5 is a top view thereof;

FIG. 6 is a bottom view thereof;

FIG. 7 is a front view showing an alternate embodiment of our new design;

FIG. 8 is a left side view thereof;

FIG. 9 is a right side view thereof;

FIG. 10 is a rear view thereof;

FIG. 11 is a top view thereof; and,

FIG. 12 is a bottom view thereof.
